(57) **CLAIM**

The ornamental design for a door handle for an escutcheon plate assembly, as shown and described.

DESCRIPTION

FIG. 1 is a perspective view of a door handle for an escutcheon plate assembly;
FIG. 2 is a front view of FIG. 1;
FIG. 3 is a back view of FIG. 1;
FIG. 4 is a right-side view of FIG. 1;
FIG. 5 is a left-side view of FIG. 1;
FIG. 6 is a top view of FIG. 1; and,
FIG. 7 is a bottom view of FIG. 1.

The portions of the article in broken lines are shown for illustrative purposes only and form no part of the claimed design.
